UNITED STATES PATENT OFFICE.

BENJAMIN W. BEADELL, OF CHICAGO, ILLINOIS, ASSIGNOR TO NATIONAL WATER-PROOF FILM COMPANY, OF CHICAGO, ILLINOIS, A CORPORATION OF ILLINOIS.

CONTAINER FOR PICTURE-FILMS AND THE LIKE.

1,019,589.

Specification of Letters Patent. Patented Mar. 5, 1912.

Application filed June 26, 1911. Serial No. 635,493.

To all whom it may concern:

Be it known that I, BENJAMIN W. BEADELL, a citizen of the United States, and resident of Chicago, county of Cook, and 5 State of Illinois, have invented certain new and useful Improvements in Containers for Picture-Films and the Like, of which the following is a specification and which are illustrated in the accompanying drawings, 10 forming a part thereof.

The invention relates to containers adapted for the storage of the films used in the projection of moving pictures; and has for its object to provide a container which shall 15 preserve the film in a pliable condition.

The films used for the projection of moving pictures commonly take the form of a long web consisting of a strip of celluloid, or similar transparent material, having a 20 gelatin picture film applied thereto upon one side. The use of these films in projecting machines requires them to be repeatedly flexed, and they are subjected to the drying influence of the lamp used in the projecting 25 machine. It is well known that in time they become hard and brittle whereby their utility is much impaired.

The present invention contemplates a container adapted to preserve the film in an 30 atmosphere laden with moisture and glycerin, whereby the film is softened and retains its flexibility.

In the accompanying drawings Figure 1 is a plan view of a container constructed in 35 accordance with the invention, the cover being removed and some of the parts being broken away; and Fig. 2 is a central transverse sectional view of the same.

The container may conveniently take the 40 form of a moisture-proof metal can comprising a cylindrical body 10, having a closed end 11 and a removable cover 12. This can is shown as being of the proper shape to receive a reel 13 having a picture 45 film 14 wound thereon, but is preferably somewhat deeper than the width of the reel.

In carrying out the invention the chamber 50 of the can is divided into separate compartments by a foraminous partition wall 15, one of the compartments, as 16, serving to receive the reel 13 and the other compartment 17 being filled with a packing 18. As shown the body wall 10 of the can is provided with a circumferential bead 19 adjacent the closed end 11 of the can, thereby

providing an internal groove which serves as a seat for the rim of the partition wall 15. The packing 18 is brought into close proximity with the film 14 wound upon the reel 13, by making the partition 15 of annular form with a flange 20 upon its inner edge, which flange is seated against and secured to the closed end 11 of the can. 60

The partition 15 is preferably made of foraminous sheet metal, and the flange 20 is 65 formed by slitting the inner edge of the partition at intervals, thereby forming it into sections, as 21, 22, each of which is turned downwardly and then inwardly to provide a foot, as 23, which rests against the closed 70 end 11 of the can. The flange 20 is permanently secured to the closed end of the can preferably with solder used in small quantities at the adjacent edges of the sections 21, 22, as indicated at 24. 75

The packing 18 preferably consists of an absorbent material, as mineral wool, moistened with a mixture of water, glycerin and a volatile oil. Oil of eucalyptus has been found to serve very well as the volatile oil, 80 as by its evaporation it causes the water and glycerin to permeate the film 14 even though the latter be tightly wound upon the reel 13. The mixture used for moistening the mineral wool preferably consists of equal parts of water and glycerin, and one-third part, by volume, of oil of eucalyptus. As the container is but little larger than the reel 13 it may be used for storing the film 85 14 whenever the latter is not in use. 90

It has been found that a film which has become hard and brittle by use is rendered flexible by storage in a container of the kind described, whereas if the container be used as a place of storage for the film at all times it will be permanently maintained in a soft and pliable condition. The cover 12 is shown as being provided with a marginal flange 25, which slips over the adjacent edge of the body wall 10 and is removably held 100 thereon by friction, as is common in cans provided with slip covers. 95

I claim as my invention—

1. A storage vessel comprising in combination, a continuous side wall, an end wall 105 fixedly connected to the said side wall, there being a circumferential groove in the side wall adjacent the said end wall, and an annular foraminous partition plate having a laterally projecting flange upon its inner 110

edge, the rim of the said plate being seated in the said circumferential groove and the laterally projecting flange of the said plate being seated against and secured to the said 5 end wall whereby an annular compartment for receiving an absorbent material is provided within the chamber of the vessel.

2. A storage vessel comprising in combination, a continuous side wall, an end wall 10 fixedly connected to the said side wall, there being a circumferential groove in the side wall adjacent the said end wall, and an annular foraminous partition plate having a

laterally projecting flange upon its inner edge, the rim of the said plate being elastically seated in the said circumferential groove and the laterally projecting flange of the said plate being seated against and secured to the said end wall whereby an annular compartment for receiving an absorbent material is provided within the chamber of the vessel. 15 20
